UNITED STATES PATENT OFFICE.

HENRY FURSTE, OF CINCINNATI, OHIO, ASSIGNOR TO THE UNITED STATES PRINTING AND LITHOGRAPH COMPANY, OF CINCINNATI, OHIO, A CORPORATION OF OHIO.

CARTON.

1,355,325.

Specification of Letters Patent.

Patented Oct. 12, 1920.

Application filed March 10, 1920. Serial No. 364,634.

To all whom it may concern:

Be it known that I, HENRY FURSTE, a citizen of the United States of America, and a resident of Cincinnati, in the county 5 of Hamilton and State of Ohio, have invented a new and useful Improvement in Cartons, of which the following is a specification.

The object of my invention is to provide 10 a folded carton that will not fall apart when the lid is raised.

Another object is to provide a carton, the ends of which can be easily folded, and locked in such folded form.

15 Another object is to provide a carton wherein the inside wrapper, used heretofore because the boxes were not formed substantial enough to contain the contents, may be dispensed with.

20 Another object is to provide a carton that will not require an outer wrapper to hold the box intact, thereby permitting advertising matter to be placed on the carton itself, such advertising being exhibited continuously while the carton is used and not 25 subject to destruction immediately the carton is opened.

These and other objects are attained by the means described herein and disclosed in 30 the accompanying drawings, in which:—

Figure 1, is a partly sectional and partly broken perspective view showing somewhat diagrammatically a box embodying my invention when assembled.

35 Fig. 2, is a plan view of an end section of an unassembled carton embodying my invention.

Fig. 3, is a modification of the locking member forming a detail of my invention.

40 My invention is of a folded carton wherein the end sections are so constructed that they may be positively locked in relation to one another when the carton is set up.

The carton A has a front a, a bottom b, a 45 back c and a top d. Attached to either end of the front a is an inner end ply a', having a slot a² formed between the front a and the inner end ply a'. A slot a³ is formed in the end inner ply. A flange a⁴ is formed 50 on a'.

On the side of bottom b is formed a tongue b'. A lap b² is attached to the tongue b' and to the side of the inner end ply a'. On the side of back c is formed an 55 outer end ply c' having a lug c² extending

therefrom. Attached to the lug c² is a lock c³. A side flap c⁴ is attached to the outer end ply c' and extends adjoiningly to the top. Similar series of extensions are formed on both ends of front a, bottom b and back c. The top flap d' is attached to the longitudinal edge of the top d.

The carton is set up as follows. The inner end plies a', tongues b' and laps b² on both sides of front a and bottom b are bent on 60 the scored lines e. These bent sections are turned on the scored lines so that they will be on the same side of the front and the bottom. The front a, together with the inner end plies a', are then bent upon the scored 70 lines f and f' so that the front will be at right angles to the bottom when so turned, and cause the edge of inner end plies a', adjacent to scored line f', to contact the bottom b.

The front a and sections a' cause 75 the lap b to turn upon the scored lines f' and g, placing lap b² between the plies a' and tongues b'. The tongues will take a position adjacent to plies a'. The end of tongue b' is then inserted through the slot 80 a³. The flanges a⁴ are then turned on the scored lines h. The back c and top d are then turned on the scored line k so that the back contacts the flanges a⁴. The outer end plies c' are turned on the scored line m so 85

that they will extend over and cover the sections a' and b'. The lug c² on which the lock c³ has been turned down on scored line s so as to contact the flat surface of c² together with the lock c³ are turned on 90 scored line t and inserted through the slot a². The lock c³ is then extended, thereby binding the outer end plies to the inner end plies and forming the end of the box. The side flaps c⁴ are bent on scored lines n 95 toward the center of the carton so formed. The top d is bent on the scored line p so as to close the top of the box. The top flap d' is bent on the scored line r and is inserted between the front, the top and the side flaps, 100 thereby making a closed container.

In the modified form of locking member shown in Fig. 3, the lock c³ is not bent downward upon lug c². In folding a carton having a locking member of this shape, the 105 edge c⁶ of the outer end ply is moved so as to be slightly below the bottom. The lock member c³ is then inserted through the slot a². The edge c⁶ is then moved toward the bottom until it registers therewith. The 110

rounded corner c^5 on the lug c^2 will enter the slot a^2 . The lock will then securely engage inside the carton, thereby binding the inner and outer end plies.

5. The slot a^3 on the inner end ply may be dispensed with where the tongue engaging feature is not desired. The tongue then can have any shape or form that will permit the assembling of the carton. The shape of the 10 tongue may be such as inclosed by the scored lines e , g and w .

What I claim is:—

1. A folded carton comprising a front having an inner end ply attached thereto 15 and having a slot between them and a flange on the inner end ply, a bottom having a tongue attached thereto and a lap attached to the tongue and the inner end ply, a back having an outer end ply, with a lug and a 20 lock attached thereto, the lock and the lug being adapted to be inserted through the slot between the front and the inner end ply, and a top.

2. A folded carton comprising a front 25 having a slotted inner end ply attached thereto and having a slot between them and a flange on the inner end ply, a bottom having a tongue, adapted to be inserted through the slotted inner end ply, attached 30 thereto and a lap attached to the tongue and the inner end ply, a back having an outer end ply with a lug and a lock attached thereto, the lock being adapted to be folded upon the lug and to be inserted with the 35 lug through the slot between the front and the inner end ply, and a top.

3. A folded carton comprising a front having a slotted inner end ply attached thereto and having a slot between them and 40 a flange on the inner end ply, a bottom having a tongue, adapted to be inserted through the slotted inner end ply, attached thereto and a lap attached to the tongue and the inner end ply, a back having an outer end

ply with a lug and a lock attached thereto, 45 the lock being adapted to be folded upon the lug and to be inserted with the lug through the slot between the front and the inner end ply and a side flap on the outer end ply, and a top having a top flap adapted to be inserted 50 in the carton adjacent the front thereof.

4. A folded carton comprising a front having a slotted inner end ply attached thereto, and having a slot between them, and a flange on the inner end ply, a bottom 55 having a tongue adapted to be inserted through the slotted inner end ply attached thereto, and a lap attached to the tongue and the inner end ply, a back having an outer end ply with a lug having a rounded 60 corner and a lock attached thereto, the lock and the lug being adapted to be inserted through the slot between the front and the inner end ply, the lock engaging the inner end ply and the front at their junction, and 65 a top.

5. A folded carton comprising a front having an inner end ply attached thereto and having a slot between them, a bottom 70 having a tongue attached thereto, a back having an outer end ply with a lug and a lock attached thereto, the lock and the lug being adapted to be inserted through the slot between the front and the inner end ply.

6. A folded carton comprising a front 75 having an inner end ply attached thereto and having a slot between them and a flange on the inner end ply, a bottom having a tongue attached thereto, a back having an outer end ply with a lug and a lock attached 80 thereto, the lock and lug being adapted to be inserted through the slot between the front and inner end ply.

In witness whereof, I have hereunto subscribed my name, this 6th day of March, 85 1920.

HENRY FURSTE.
